CLAIM

The ornamental design for a generator with mounting cart, as shown and described.

DESCRIPTION

FIG. 1 is a front perspective view of a generator with mounting cart showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a side elevational view thereof.
